UNITED STATES PATENT OFFICE.

WILLIAM JAMES EVANS, OF NEW YORK, N. Y., ASSIGNOR TO McKESSON & ROBBINS, OF SAME PLACE.

DESIGN FOR AN ATOMIZER-BODY.

SPECIFICATION forming part of Design No. 22,683, dated August 8, 1893.

Application filed June 22, 1893. Serial No. 478,519. Term of patent 14 years.

To all whom it may concern:

Be it known that I, WILLIAM JAMES EVANS, a citizen of the Dominion of Canada, residing at New York, in the county of New York and State of New York, have produced a certain new and original Design for an Atomizer-Body, of which the following is a specification, reference being had to the accompanying drawing.

10 This invention relates to an original design for an atomizer body and consists in the peculiar shape and position of the several parts, as shown in the accompanying drawing wherein the atomizer body is shown in perspective.

15 The design as represented in the drawing consists of a cup A, having a rounded or curved base from which extends the suction tube B which is curved downwardly and outwardly below the cup and upward along the

side of and in close proximity to the same, its 20 upper end being extended above the top of the cup and bent or carried out at an angle, as at B', terminating in the nozzle. C is the air tube.

The essential feature of the design is the 25 curving of the lower end and position of the suction tube relative to the cup.

Having thus described the invention, what is desired to be secured by Letters Patent is—

The design for an atomizer body, substantially as described and shown.

In testimony whereof I affix my signature in presence of two witnesses.

WILLIAM JAMES EVANS.

Witnesses:

JAMES R. OWEN,
C. R. DICKERSON.
